BATHTUB

Horst Godfrey Bonsack, Flat 17, 51 South St.,
London W. 1, England

Filed Nov. 12, 1973, Ser. No. 415,227

Claims priority, application Great Britain June 4, 1973

Term of patent 14 years

Int. Cl. D23—02

U.S. Cl. D23—55

Fig. 1

Fig. 2

Fig. 3

Fig. 4

FIG. 1 is a perspective view taken from the top and front of a bathtub showing my new design;

FIG. 2 is a bottom plan view thereof;

FIG. 3 is an elevational view taken from one side, the opposite side being a mirror image of the side shown; and

FIG. 4 is a rear elevational view thereof.

I claim:

The ornamental design for a bathtub, as shown and described.
